REFRIGERATION

Donald G. Smellie, Canton, Ohio, assignor to The Hoover Company, North Canton, Ohio, a corporation of Ohio

Application July 20, 1938, Serial No. 220,200

25 Claims. (Cl. 62—105)

This invention relates to refrigerating systems and more particularly to evaporator structures particularly adapted for use in absorption refrigerating systems.

Heretofore it has been customary to provide refrigerating systems with trays in which water is frozen in the form of cubes or small blocks of ice. These systems had the disadvantage that the trays adhere with considerable force to the supporting shelves in the evaporator and a large percentage of the ice must be melted in order to release the ice cubes. Accordingly, it is an object of this invention to provide a refrigerating system in which ice is frozen in the form of small blocks which are readily removable individually and collectively from the refrigerating mechanism.

It is a further object of this invention to provide a large body of cold water which is exposed to the air within the box to maintain the humidity therein within reasonable values.

It is another object of the invention to provide a refrigerating system in which a large body of cold drinking water is always available.

It is a further object of the invention to provide a refrigerating system which is provided with a movably mounted water tank so constructed and arranged that a plurality of ice blocks are frozen on the wall of the tank after which the tank is shifted bodily for a small distance and other ice blocks are formed while those originally formed melt free of the wall of the water container.

It is a further object of the invention to provide a refrigerating system which is controlled in response to box temperature conditions and which relates the rate of ice freezing to the rate of heat transfer from the storage compartment; that is, the rate of ice freezing will increase with increases in ambient temperature.

Other objects and advantages of the invention will become apparent as the description proceeds when taken in connection with the accompanying drawings, in which:

Figure 1 is a diagrammatic illustration of a refrigerating system embodying my invention;

Figure 2 is a side elevational view partly in section and drawn to an enlarged scale of the evaporator illustrated in Figure 1;

Figure 3 is a partial sectional view of the evaporator illustrated in Figure 2;

Figure 4 is a sectional view taken along the line 4—4 of Figure 2 and looking in the direction of the arrows;

Figure 5 is a bottom plan view of a modified form of the invention;

Figure 6 is a view taken along the line 6—6 of Figure 5 and looking in the direction of the arrows;

Figure 7 is a view taken along the line 7—7 of Figure 5 and looking in the direction of the arrows;

Figure 8 is a bottom plan view of a third modification of the invention;

Figure 9 is a view taken along the line 9—9 of Figure 8 and looking in the direction of the arrows; and

Figure 10 is a view corresponding to Figure 8 with the parts in a slightly different position.

For purposes of convenience I have illustrated my invention as being applied to a continuous three-fluid absorption refrigerating system; however, it is to be understood that it is equally applicable to other forms and types of refrigerating systems and that the system herein disclosed is selected for purposes of illustration only.

Referring now to Figure 1, it will be seen that I have illustrated a continuous three-fluid absorption refrigerating system comprising a boiler B, an analyzer D, a rectifier R, an air-cooled condenser C, an evaporator E, a gas heat exchanger G, an absorber A, a weak solution reservoir S, a liquid heat exchanger L, and a circulating fan F driven by an electrical motor M. The elements just described are suitably interconnected to form a plurality of gas and liquid circuits which taken together comprise the complete system.

The refrigerating system is suitably charged with a refrigerant such as ammonia, an absorbent such as water, and an inert gas such as nitrogen or hydrogen.

The boiler B is heated by any suitable form of gas burner 11 which is provided with a safety cut-off device 12. The burner 11 is supplied with fuel from the line 13 through a solenoid valve 14 and a conduit 15. A by-pass 16 is provided around the valve to provide a small supply of gas which will be sufficient to maintain an igniting flame on the burner 11.

The boiler B normally contains a solution of refrigerant in an absorbent which will liberate refrigerant vapor when subjected to heat. The refrigerant vapor liberated in the boiler passes upwardly through the analyzer in counterflow relationship to strong solution flowing downwardly therethrough. Absorption solution vapor generated in the boiler condenses in the analyzer, the heat of condensation serving to liberate fur-

ther refrigerant vapor from the strong solution. The refrigerant vapor is conveyed from the analyzer to the condenser C through a conduit 21 which includes an air-cooled rectifier R. The rectifier serves to condense any vapor of absorption solution which may pass through the analyzer. The weak solution formed in the boiler by the generation of refrigerant vapor is conveyed therefrom into the upper end of the air-cooled absorber A through a conduit 23, liquid heat exchanger L, and conduit 24. It is apparent that the upper portion of the absorber is at an elevation considerably above the liquid level normally prevailing within the boiler-analyzer system; therefore, it is necessary to provide an elevating device for the weak solution. For this purpose a conduit 25 is interconnected between the discharge conduit 26 of the circulating fan F and the conduit 24 at a level below the normal liquid level prevailing in the boiler-analyzer system whereby the weak solution is elevated into the absorber by gas lift action. The weak absorption solution flows downwardly through the absorber in counterflow relationship to a refrigerant vapor pressure equalizing medium mixture flowing upwardly therethrough. The weak solution removes the refrigerant vapor by absorption to form strong solution. The strong solution formed in the absorber is discharged through a conduit 28 into the solution reservoir S from which it is returned to the upper portion of the analyzer D through a conduit 29, liquid heat exchanger L, and a conduit 30.

The lean pressure equalizing medium formed in the absorber is withdrawn from the upper portion thereof into the suction inlet of the circulating fan F through a conduit 31. The lean pressure equalizing medium is placed under pressure in the fan and is discharged therefrom through a conduit 26, gas heat exchanger G, and conduit 33 into the bottom portion of the evaporator E which will be described more fully hereinafter. The pressure equalizing medium circulates upwardly through the evaporator in counterflow relationship to liquid refrigerant flowing downwardly therethrough. The liquid refrigerant is supplied to the upper portion of the evaporator through a conduit 35 which connects to the bottom portion of the air-cooled condenser C. The refrigerant liquid evaporates into the pressure equalizing medium to produce refrigeration, and the resulting rich mixture is returned to the gas heat exchanger through a conduit 36. The rich pressure equalizing medium is conveyed from the gas heat exchanger to the bottom portion of the absorber A through a conduit 31. The rich mixture passes upwardly through the absorber in counterflow relationship to absorption solution in the manner described previously.

Electrical energy is supplied through a pair of wires 39 and 40. The line 40 connects directly to the motor M and to the solenoid valve 14. The line 39 connects directly to one contact of a thermostatic switch 42. The thermostatic switch 42 is connected by means of a wire 43 to the circulating motor M and the solenoid valve 14. The arrangement is such that closure of the switch 42 simultaneously energizes the motor and the solenoid valve whereby refrigerant vapor is generated in the boiler and the fluids in the system are circulated by the fan. The thermostatic switch 42 is preferably positioned within the storage compartment of the refrigerator to be responsive to the temperature thereof. A demand for refrigeration corresponding to a rise in box 75

temperature causes closure of the thermostatic switch 42 and energization of the refrigerating system.

The evaporator E will now be described in detail in connection with Figures 1 to 4. The evaporator comprises a lower low temperature coil section 46 which is connected to an upper ice-freezing coil section 47 by a riser conduit 48. The evaporator section 46 is illustrated as comprising four coil sections whereas the evaporator section 47 is illustrated as comprising two coil sections and a transverse front section joining the two. A conduit 49 extends between the section 46 and the strong solution conduit 29 to drain excess refrigerant from the evaporator. The evaporator sections 46 and 47 are completely encased in insulating material 50 which is shaped to form a freezing compartment 51. Internally the freezing compartment is defined by an inner wall 52 which is in thermal contact with the lower coil section 46 and is spaced and insulated from the upper coil section 47. The upper coil section 47 is provided with a plurality of spaced freezing pads 54 which project upwardly through the top portion of the insulating material 50. The side and end walls of the casing 51 extend upwardly slightly beyond the top portion of the insulating material 50 to form a depression 55 therein. A water tank 56 of lesser length than the depression 55 is mounted therein. The water tank 56 is provided on the sides and ends thereof with downwardly extending flanges 58 which are lined with packing material 59. The packing material rides upon the upper end of the side walls of the casing 51 and seals the depression 55 from the atmosphere within the refrigerating compartment. This tends to prevent accumulation of frost within the depression 55. A slight amount of heavy oil, enough to insure that a thin film of oil will be maintained, between the freezing pads 54 and the bottom of the tank 56, is maintained in the depression 55 in order to prevent the tank 56 from freezing to the freezing pads and to permit the tank to be moved readily. The front and rear flanges 58 extend longitudinally beyond the tank 56 a distance equal to the difference in length between the length of the tank and the length of depression 55 whereby the tank may be shifted longitudinally of the depression 55 without breaking the seal between the flanges 58 and the side walls of the casing 51.

In order to operate the water tank 56 an electric motor 60 is secured in any suitable manner on the rear wall 34 of the refrigerating chamber of the refrigerator cabinet. The electric motor is provided with a suitable reduction gearing, not shown, which actuates a crank arm 61. The crank arm 61 is pivotally connected to a connecting rod 62 which is pivotally mounted at 63 on the rear flange 58 of the vessel 56. Power is supplied to the motor from a pair of supply lines 64. The motor is internally provided with a suitable reversing mechanism or with a suitable cut-off mechanism of known type which will operate to de-energize the same after the crank 61 has rotated through an arc of 180 degrees in either direction. A motor control housing 65 is shown mounted on the front portion of the vessel 56; the housing 65 may equally well be positioned on the rear, side, or within the vessel 56. A pair of stationary contacts 66 and 67 are mounted upon and insulated from the housing 65. The contacts 66 and 67 are connected to the motor by wires 68 and 69, respectively. A thermostatic bellows 70 is rigidly supported within the hous-

ing 65 and carries a contact 71 which is adapted to close the circuit through either of the stationary contacts 66 and 67. Contact 71 is connected to the motor 60 by a wire 72. The bellows 70 is connected to a thermostatic bulb 73 which is mounted within the tank 56 in position to be contacted by ice blocks frozen on the bottom forward position thereof.

The operation of this form of the invention will now be described. Assuming that the temperature in the storage compartment of the refrigerator is such as to demand refrigeration, the thermostat 42 will close and energize the circulating motor M and the burner 11 whereby refrigeration will be produced. The liquid refrigerant will flow downwardly through the evaporator E in counterflow relationship to the pressure equalizing medium which is propelled upwardly therethrough by the fan F. The evaporator sections 46 will operate at a lower temperature than the evaporator section 47 by reason of the lower ammonia concentration in the inert gas circulating therethrough. The insulation provided in the compartment 51 prevents frost from forming thereon and permits the coils 46 to reach a very low temperature suitable for freezing desserts, for example. Normally, the coils 46 will reduce the temperature of the compartment 51 to a low value at which it will be maintained by reason of the insulation provided therefor. The refrigeration produced in the upper coil section 47 will cause blocks of ice to freeze within the water in the tank 56 on those portions of the tank bottom which are in direct thermal contact with the freezing pads 54. The ice will continue to be frozen in the bottom of the tank 56 until the ice blocks formed above the freezing pad 54 on the front portion of the evaporator coil have frozen around the thermostatic bulb 73. When the thermostatic bulb 73 has been frozen into the ice block, the bellows 70 will contract and close the circuit through the contacts 71 and 67 which will energize the motor 60 in such fashion as to cause the tank 56 to be pushed forwardly to the position shown in Figure 2. When the tank reaches its forward position, the motor 60 will automatically de-energize itself and will remain in de-energized condition until the bellows 70 has expanded sufficiently to close the circuit to the contacts 66 and 71. When the tank reaches its forward position, the ice block which has frozen around the bellows 73 has been removed from proximity to the freezing coil and immediately begins to melt free of the bottom of the tank 56. The bulb 73 is positioned laterally with respect to the ice block which will build up over the front pad 54 as shown in Figures 3 and 4. The arrangement is such that the ice block cannot immediately float to the surface of the water in the tank 56 when it is melted free of the bottom thereof, but it must remain in contact with the bulb 73 a period of time sufficient to permit it to rock around the bulb 73, as shown in Figure 4, whereupon it will float to the surface of the water in the tank. When the bulb 73 is disengaged from actual contact with ice, it begins to warm and eventually will expand the bellows sufficiently to close the circuit between the contacts 66 and 71 whereupon the motor will be energized and will draw the tank 56 to its rearmost position which will again bring the bulb 73 in position directly above the front freezing pad 54.

In short, it will be seen that my evaporator freezes a plurality of spaced blocks of ice within

5 a body of water whereupon the tank containing the body of water is shifted with respect to the freezing pads to remove the previously frozen ice from contact therewith and to bring fresh areas 10 of the tank bottom into contact with the freezing pads. The previously frozen ice blocks then melt free of the bottom of the tank and float to the surface of the water therein from which they may conveniently be ladled out and used as desired.

15 Referring now to Figures 5 to 7, there is disclosed a modification of the invention. This form of the invention is adapted to be used with a refrigerating system exactly as described in connection with Figure 1. In this form of the invention the ice-freezing coil section 80 of the evaporator is formed into a ring which is enclosed in insulation 81 retained by a housing 82. The evaporator coil 80 is provided with a plurality, six being shown, of freezing pads 83 which 20 project above the insulation 81. The side walls of the casing 82 extend upwardly beyond the upper portion of the insulation 81 to form an annular depression which receives a downwardly projecting annular portion of a cylindrical freezing tank 85; the bottom portion of the tank 85 is provided with overhanging sealing flanges 86 which engage the wall 82 to seal the depression in the insulating material 81 from the atmosphere within the refrigerator. This depression is 25 also provided with a body of low temperature oil for reasons fully developed in connection with Figure 1.

30 This form of the invention is provided with a drive motor 60', crank 61', connecting rod 62', pivotal connection 63', corresponding to the elements 60 to 63, inclusive, described in connection with Figure 1 with the exception that the motor 60' rotates the water tank 85 whereas in 35 connection with Figure 1, the tank was shifted longitudinally. The bottom central portion of the tank 85 is provided with a downwardly projecting sleeve 87 which receives a rigidly mounted shaft 88. The weight of the tank 85 is carried 40 by the evaporator coil 80; the guide post 88 merely serves to maintain the annular projecting portion of the tank 85 in a central position with respect to the evaporator coil whereby it does not bind when rotated by the motor.

45 50 An electrical switching mechanism and thermostatic control mechanism is carried by the bottom portion of the tank 85 within the area enclosed by the ring-shaped evaporator. These elements correspond exactly to elements previously described in connection with Figure 1 and are therefore given the same reference characters primed.

55 It is to be understood that this form of the invention will be provided with a dessert freezing storage compartment corresponding to the compartment 51 fully described in connection with Figure 1. As shown, the insulation for the compartment would be entirely separate from that provided for the ice freezing evaporator coil section 80; however, the coil 80 could be 60 embedded in the top portion of a compartment in the same manner in which the coil 47 is embedded in the top portion of the compartment 51 described in connection with Figure 1.

65 70 In operation, ice freezes above the pads 83 until the thermostatic bulb 73' is frozen in sufficiently to contract the bellows 70' and to make the circuit through the contact 67' and 71' which will energize the motor 60' to cause it to rotate the tank 85 in a counter-clockwise direction as

viewed in Figure 1. The connecting rod 62' and the crank 61' are so proportioned that the tank 85 will be shifted a short distance, sufficient to remove the ice blocks from the areas affected by the pads 83. This will allow previously frozen ice blocks to melt away from the freezing pads so that they may float to the surface of the water in the tank 85. The arrangement of the bulb 73' corresponds to the arrangement of the bulb 73 described in connection with Figure 1 in order to prolong the melting period for one of the previously frozen ice blocks, a length of time sufficient to permit ice blocks to freeze over the freezing pads in the position of the tank 85 not shown in Figure 5.

Referring now to Figures 8 to 10, there is illustrated a third modification of the invention. In this form of the invention the tank, the evaporator coil, the insulating structure and the sealing structure are identical with those disclosed in connection with Figures 5 to 7 and are given the same reference characters primed. In this form of the invention, the tank 85' is rotated by a thermostatic mechanism without the aid of a prime mover corresponding to the electrical motors 60 and 60' previously described. Three equally spaced webs 90, 91 and 92 project inwardly from the casing 82' to the center of the cylindrical tank 85' and carry at their junction a guide mechanism similar to the guide mechanisms 87, 88 described in connection with Figures 5 to 7. The webs 90, 91 and 92 are equally spaced apart around the circumference of the ring-shaped evaporator coil 80'. A pair of thermostatic bellows 95 and 96 are rigidly carried by the central bottom portion of the tank 85'. The bellows 95 and 96 are pivotally connected to actuating arms 97 and 98, respectively, which pass through suitable openings in the web members 90 and 92, respectively. The actuating arms 97 and 98 are provided with enlarged heads on the sides of the web members 90 and 92 opposite to their respective actuating bellows whereby contraction of either bellows will tend to pull its associated web 90 toward the contracted bellows. The bellows 95 and 96 are provided with freezing bulbs 101 and 102, respectively. The bulbs 101 and 102 extend into the bottom annular portion of the tank 85' in position to be contacted by ice blocks frozen therebelow. The positioning of the bulbs 101 and 102 is such that one or the other is always in position to be frozen into one corner or the other of an ice block frozen above the freezing pads marked "P."

The operation of this form of the invention will now be described. In Figure 8, the bellows 96 has just contracted by reason of the bulb 102 being frozen into an ice pad. The contraction of the bellows 96 has rotated the tank 85' in a clockwise direction, as viewed in Figure 8. The rotating force is exerted through the bellows and the actuating element 98 which engages the stationary web member 92. This movement of the tank 85' has shifted the previously frozen ice block away from the freezing pads 83' and has brought fresh areas of the annular portion of the tank 85' into contact with the freezing pads 83'. This movement of the tank has also shifted the bulb 101 into position to be frozen into the corner of an ice block freezing over the freezing pad P. Should the bellows 95 contract by reason of the bulb 101 being frozen into an ice block before the bulb 102 has been freed from its associated ice block, no movement of the freezing tank will occur because of the

substantially equal and opposite forces tending to move the same. However, if the bulb 102 is freed of contact with ice before the bulb 101 is frozen to contract the bellows 95, the bellows 96 will merely expand and the actuating element 98 will slide through the associated web member 92 without tending to impart movement to the tank 85'. When the bellows 102 has been freed of contact with its associated ice block and the bellows 101 has been frozen into its associated ice block, the bellows 96 will be expanded, and the bellows 95 will have contracted to shift the tank 85' in a counterclockwise direction, as viewed in Figure 10. The above described cycle is then repeated; that is, the bellows 95 and 96 alternately expand and contract and in so doing they rotate the tank 85' back and forth through a small arc of movement thereby alternately freezing and releasing ice blocks on certain portions of the bottom portion thereof.

Obviously, the tank could be operated by an expansible movement of the bellows if desired. In this event, the actuating bellows would shift its associated bulb over a freezing pad. In the form shown, an actuating movement of either bellows shifts the bulb associated with the other bellows over a freezing pad. While the bellows actuating mechanism has been disclosed only in connection with a rotary tank it is obvious that such an actuating mechanism could be utilized to shift other types of water tanks.

It will be obvious that all the modifications of the invention above illustrated and described may be applied to any type of refrigerating apparatus; an absorption apparatus was selected merely as an example of one embodiment of the invention.

The freezing mechanisms above described have the great advantage that ice is alternately frozen in different areas of the freezing tank of the same evaporator section and without in any fashion interfering with the interior mechanism of the refrigerating system for example, by diverting fluids from one circuit therein into another. This mechanism entirely eliminates all valve and internal switching mechanisms whereby the refrigerating system may be conventional provided that the evaporator coil carries spaced freezing pads upon which a water tank may be rested.

The rate at which ice is formed is a function of the ambient temperature for the following reasons. The ambient temperature will determine the frequency at which control mechanism will energize the refrigerating system and the length of time required for the refrigerating mechanism to lower the box temperature to the desired value. Therefore, rate of ice freezing will be high in hot weather and low in cold weather. This is a convenient arrangement because the demand for ice is greatest in hot weather.

The water tanks, which may be finned if desired, are continually swept by the air within the refrigerating compartment and so as to maintain the temperatures within that compartment at safe values for preservation of foodstuffs. Also the large exposed surface of the body of water serves to maintain the humidity within the refrigerating cabinet within reasonable values. If desired, a loose fitting cover may be placed over the tank 56 to prevent accidental contamination of the water therein contained by material being dropped into the tank. The cabinet may have a top opening to allow access to

the ice cubes floating within the tank such as that disclosed in the co-pending application of Curtis C. Coons, Serial No. 161,563, filed August 30, 1937.

In summation it may be said that my invention provides a mechanism whereby a plurality of ice blocks are available, freely floating within a body of water; the ice is frozen in a movably mounted tank which is automatically shifted whenever the ice has reached a predetermined size to permit previously formed ice to melt free from the bottom of the tank and to cause new blocks of ice to be frozen in new areas at the bottom of the tank. In addition, the freezing tanks may be provided with water spigots to provide cold drinking water.

While I have illustrated and described three embodiments of my invention, it is not limited thereto but may be embodied in numerous other modifications without departing from the spirit thereof or the scope of the appended claims.

I claim:

1. Refrigerating apparatus comprising an evaporator, an ice freezing tank mounted to contact said evaporator at a plurality of spaced points, and means operable to shift said tank with respect to said points in order to release previously frozen ice therefrom and to cause said evaporator to freeze ice at newly selected points.

2. Refrigerating apparatus comprising a cooling unit, a movably mounted water tank in heat exchange relationship with portions of said cooling unit, and means for changing the relative positions of said tank and cooling unit, said means including thermostatic means actuated by formation and melting of ice in said tank.

3. Refrigerating apparatus comprising a cooling unit, a movably mounted water tank in heat exchange relationship with portions of said cooling unit, and means for changing the relative positions of said tank and cooling unit, said means including thermostatic means having a portion within said tank, the portion of said thermostatic means in said tank being so positioned that an ice block frozen therearound must melt sufficiently to pivot about said portion and between said portion and the bottom of said tank to float to the surface of the water in said tank.

4. Refrigerating apparatus comprising a cooling unit, a movably mounted water tank in heat exchange relationship with portions of said cooling unit, and means for changing the relative positions of said tank and cooling unit, said means including thermostatic means having a portion within said tank in position to be frozen into a nice block adjacent an edge thereof.

5. Refrigerating apparatus comprising a cooling unit, means for circulating a cooling medium through said unit, a plurality of freezing pads on said cooling unit, a water tank mounted in heat exchange relationship with said freezing pads, and means for periodically altering the relative positions of said tank and said cooling unit, said means comprising a pair of temperature responsive elements connected to shift said tank in opposite directions.

6. Refrigerating apparatus comprising a cooling unit, means for circulating a cooling medium through said unit, a plurality of freezing pads on said cooling unit, a water tank mounted in heat exchange relationship with said freezing pads, means for periodically altering the relative positions of said tank and said cooling unit, said means comprising a pair of temperature responsive elements connected to shift said tank in opposite directions.

sive elements connected to shift said tank in opposite directions, each of said temperature responsive elements comprising an expansible bellows fixed to said tank, a connection between said bellows and a fixed element, and a bulb element mounted within said tank, said bulb elements being positioned in such fashion that actuating movement of either bellows shifts one of said bulbs in position to be contacted by ice formed in said tank above one of said freezing pads.

7. Refrigerating apparatus comprising a cooling unit, means for circulating a cooling medium through said unit, a plurality of freezing pads on said cooling unit, a water tank mounted in heat exchange relationship with said freezing pads, and means for periodically removing the portions of said tank in heat exchange relationship with said pads out of heat exchange relationship therewith.

8. Refrigerating apparatus comprising a cooling unit, means for circulating a cooling medium through said unit, a plurality of freezing pads on said cooling unit, a water tank mounted in heat exchange relationship with said freezing pads, means for periodically altering the relative positions of said tank and said cooling unit, and means responsive to the formation of a predetermined depth of ice over said freezing pads for controlling said altering means.

9. Refrigerating apparatus comprising a cooling unit, means for circulating a cooling medium through said unit, a plurality of freezing pads on said cooling unit, a water tank mounted in heat exchange relationship with said freezing pads, and power-driven means for periodically shifting said tank with respect to said freezing pads.

10. Refrigerating apparatus comprising a cooling unit, means for circulating a cooling medium through said unit, a plurality of freezing pads on said cooling unit, a water tank mounted in heat exchange relationship with said freezing pads, power-driven means for periodically shifting said tank with respect to said freezing pads, and means constraining said tank to longitudinal movement.

11. Refrigerating apparatus comprising a cooling unit, means for circulating a cooling medium through said unit, a plurality of freezing pads on said cooling unit, a water tank mounted in heat exchange relationship with said freezing pads, power-driven means for periodically shifting said tank with respect to said freezing pads, and means constraining said tank to axial movement.

12. Refrigerating apparatus comprising a cooling unit, a plurality of freezing pads projecting from said unit, means enclosing said unit except for the ends of said pads, a water tank movably mounted in contact with said pads, and means sealing the area of said tank in proximity to said pads from the ambient atmosphere.

13. Refrigerating apparatus comprising a cooling unit, a plurality of freezing pads projecting from said unit, means enclosing said unit except for the ends of said pads, a water tank movably mounted in contact with said pads, and means sealing the area of said tank in proximity to said pads from the ambient atmosphere, said sealing means including sealing elements carried by said tank and engaging said means enclosing said cooling unit.

14. Refrigerating apparatus comprising a cooling unit, a plurality of freezing pads projecting from said unit, means enclosing said unit except for the ends of said pads, a water tank movably

mounted in contact with said pads, means sealing the area of said tank in proximity to said pads from the ambient atmosphere, and a body of lubricant between said tank and the means enclosing said unit.

15. Refrigerating apparatus comprising a casing element of insulating material, a freezing chamber formed within said casing, a cooling unit, portions of said unit being embedded in said insulating material in heat exchange relation with said chamber, other portions of said cooling unit being imbedded in said insulating material and out of heat exchange relation with said chamber, and a movably mounted water tank in heat exchange relation with said last mentioned portions of said cooling unit.

16. Refrigerating apparatus comprising a refrigerating compartment, a cooling unit in said compartment, a water tank mounted in heat exchange relationship with said cooling unit at a plurality of points, mechanism for automatically shifting the position of said tank when ice has formed to a predetermined depth at said points, and means responsive to the demand for refrigeration in said compartment for controlling said cooling unit.

17. Absorption refrigerating apparatus comprising a solution circuit including a boiler and an absorber, an inert gas circuit including an evaporator and said absorber, means for supplying refrigerant liberated from solution in said boiler to said evaporator in liquid phase, a water container in heat transfer relationship with said evaporator at a plurality of points, means for periodically changing the relative positions of said evaporator and said container to break the heat transfer relationship between said evaporator and said container at said plurality of points to permit previously formed ice blocks to melt free thereof and to establish heat transfer relationship between said evaporator and said container at a plurality of other points to produce a new group of ice blocks.

18. Absorption refrigerating apparatus comprising a solution circuit including a boiler and an absorber, an inert gas circuit including an evaporator and said absorber, means for supplying refrigerant liberated from solution in said boiler to said evaporator in liquid phase, said evaporator including an ice-freezing section and a fast freezing section, an insulated compartment receiving said fast freezing section, a water container in heat transfer relationship with said ice-freezing section at a plurality of points, means for periodically changing the relative positions of said ice-freezing section and said container to break the heat transfer relationship between said evaporator and said container at said plurality of points to permit previously formed ice blocks to melt free thereof and to establish heat transfer relationship between said evaporator and said container at a plurality of other points to produce a new group of ice blocks.

19. Absorption refrigerating apparatus comprising a solution circuit including a boiler and an absorber, an inert gas circuit including an evaporator and said absorber, means for supplying refrigerant liberated from solution in said boiler to said evaporator in liquid phase, said evaporator including an ice freezing section and a fast freezing section, said ice freezing and fast freezing sections being so arranged that the inert gas flows through the fast freezing and ice freezing sections in that order and the refrigerant liquid flows through said sections in counterflow re-

lationship to the inert gas, an insulated compartment receiving said fast freezing section, a water container in heat transfer relationship with said ice-freezing section at a plurality of points, means for periodically changing the relative positions of said ice freezing section and said container to break the heat transfer relationship between said evaporator and said container at said plurality of points to permit previously formed ice blocks to melt free thereof and to establish heat transfer relationship between said evaporator and said container at a plurality of other points to produce a new group of ice blocks.

20. Absorption refrigerating apparatus comprising a solution circuit including a boiler and an absorber, an inert gas circuit including an evaporator and said absorber, means for supplying refrigerant liberated from solution in said boiler to said evaporator in liquid phase, a water container in heat transfer relationship with said evaporator at a plurality of points, means for periodically changing the relative positions of said evaporator and said container to break the heat transfer relationship between said evaporator and said container at said plurality of points to permit previously formed ice blocks to melt free thereof and to establish heat transfer relationship between said evaporator and said container at a plurality of other points to produce a new group of ice blocks.

21. Absorption refrigerating apparatus comprising a solution circuit including a boiler and an absorber, an inert gas circuit including an evaporator and said absorber, means for supplying refrigerant liberated from solution in said boiler to said evaporator in liquid phase, a water container in heat transfer relationship with said evaporator at a plurality of points, means for periodically changing the relative positions of said evaporator and said container to break the heat transfer relationship between said evaporator and said container at said plurality of points to permit previously formed ice blocks to melt free thereof and to establish heat transfer relationship between said evaporator and said container at a plurality of other points to produce a new group of ice blocks, said last mentioned means including thermostatic control means responsive to the formation of ice blocks to control the periodic change in the relative positions of said evaporator and said water container.

22. Absorption refrigerating apparatus comprising a solution circuit including a boiler and an absorber, an inert gas circuit including an evaporator and said absorber, means for supplying refrigerant liberated from solution in said boiler to said evaporator in liquid phase, said evaporator including an ice-freezing section and a fast-freezing section, an insulated compartment receiving said fast-freezing section to refrigerate the interior thereof, a water container in heat transfer relationship with said ice freezing section at a plurality of points, means for periodically changing the relative positions of said ice-freezing section and said container to break the heat transfer relationship between said evaporator and said container at said plurality of points to permit previously formed ice blocks to melt free thereof and to establish heat transfer relationship between said evaporator and said

23. Absorption refrigerating apparatus comprising a solution circuit including a boiler and an absorber, an inert gas circuit including an evaporator and said absorber, means for supplying refrigerant liberated from solution in said boiler to said evaporator in liquid phase, said evaporator including an ice freezing section and a fast freezing section, said ice freezing and fast freezing sections being so arranged that the inert gas flows through the fast freezing and ice freezing sections in that order and the refrigerant liquid flows through said sections in counterflow re-

container at a plurality of other points to produce a new group of ice blocks, said ice freezing section being embedded in the insulation of said compartment except for those portions thereof which are in heat transfer relationship with said water container.

23. Refrigerating apparatus comprising a cooling unit, means for supplying a cooling medium to said cooling unit, a water container having a limited area of the wall thereof in heat exchange relationship with said cooling unit to form ice on the inner surface of that portion of the wall of said container which is in heat exchange relationship with said cooling unit, means movably mounting said container to allow movement thereof to remove one area of the wall thereof out of heat exchange relationship with said cooling unit and to establish heat exchange relationship between said cooling unit and another area of the wall thereof, an electric motor operatively connected to said container for moving the same, and control means for said motor arranged to energize the same to move said container when a predetermined amount of ice has formed on the inner surface of that portion of the wall thereof which is in heat exchange relationship with said cooling unit.

24. Refrigerating apparatus comprising a cooling unit, means for supplying a cooling medium to said cooling unit, a water container having a limited area of the wall thereof in heat exchange relationship with said cooling unit to form ice on the inner surface of that portion of the wall

of said container which is in heat exchange relationship with said cooling unit, means movably mounting said container to allow movement thereof to remove one area of the wall thereof out of heat exchange relationship with said cooling unit and to establish heat exchange relationship between said cooling unit and another area of the wall thereof, thermostatic means operatively connected to said movable container for moving the same when a predetermined amount of ice has formed on the inner surface of that portion of the wall thereof which is in heat exchange relationship with said cooling unit.

10 25. Refrigerating apparatus comprising a casing element of insulating material, a freezing chamber formed within said casing, a cooling unit, portions of said unit being embedded in said insulating material in heat exchange relation with said chamber, other portions of said cooling unit being embedded in said insulating material and out of heat exchange relation with said chamber, said last mentioned portion of said cooling unit including heat conducting means

20 projecting to the surface of said insulating material, a movably mounted water tank including a surface exceeding the area of said heat conducting means in heat exchange relation with said heat conducting means, and means operable in response to the formation of ice within said water tank for moving said tank with respect to said heat conducting means.

DONALD G. SMELLIE.
